SAFETY HAT

Raymond A. Smith, Bradford Woods, and Roger I. Protas,
Pittsburgh, Pa., assignors, by mesne assignments, to
Mine Safety Appliances Company, a corporation of
Pennsylvania

Filed Feb. 9, 1962, Ser. No. 68,736

Term of patent 14 years

(Cl. D3—13)

FIG. 1

FIG. 2

FIG. 3

FIG. 4

FIG. 5

FIG. 1 is a rear elevational view of a safety hat embodying our invention;

FIG. 2 is a front elevational view thereof;

FIG. 3 is a top plan view thereof;

FIG. 4 is a bottom perspective view thereof showing the interior of the safety hat or the like; and

FIG. 5 is a side elevational view thereof.

The essential features of our design reside in the portions shown in full lines on the drawing.

We claim:

The ornamental design for a safety hat, as shown and described.
